UNITED STATES PATENT OFFICE.

GEORGE BOULTON, OF ROCHESTER, NEW YORK, ASSIGNOR TO UNITED SHOE MACHINERY CORPORATION, OF PATERSON, NEW JERSEY, A CORPORATION OF NEW JERSEY.

LINING-TRIMMING MACHINE.

Application filed May 14, 1924. Serial No. 713,241.

In the manufacture of certain kinds of fancy shoes, it is customary to die out ornamental openings in the upper, to attach the lining to the upper by stitches which extend 5 along the edges of these openings, and later to cut out those portions of the lining which are exposed by the died-out openings in the upper. The portions of the lining which are thus exposed are commonly called "panels", 10 and the operation of cutting them out as "panel cutting."

This panel cutting may be done in the stitching-room before the lined upper has been attached to the sole or insole and while 15 it, or portions of it, may be spread out substantially flat; but preferably the cutting is done in the packing-room after the shoe is otherwise complete, since, if the cutting is done in the stitching-room, the subsequent 20 stretching of the upper during the pulling-over and lasting operations is liable to distort the ornamental openings.

Hitherto the cutting of panels from otherwise finished shoes has been performed almost entirely by hand, although a few machines have gone into use which are capable 25 of cutting out panels in the more readily accessible portions of the upper, such as the side portions. Many shoes, however, have 30 panels so located (for example in the toe portion of the upper) that it is impossible with machines heretofore known to cut them out.

The general object of the present invention is to provide a machine for performing 35 this and similar operations upon any locality of the shoe upper.

One obstacle which has heretofore prevented the cutting out of panels not readily 40 accessible has been that the work support, as well as the arm or other member by which it has been carried, has been stationary so that the shoe could be turned in one direction or the other during the cutting operation 45 only until such turning movement was arrested by contact of some part of the upper of the shoe with the work support or carrier. According to one feature of the present invention, the carrier for the cutting block or 50 work support is mounted for swinging movement about an axis so located that the relation between the block and the cutter, which cooperates with it to sever the work, is not disturbed by such movement. The carrier

illustrated is of a general U-shape, its arms 55 being substantially horizontal and located one above the other, the cutting block being carried at the extremity of one of the arms. With such a construction, a shoe having a panel not readily accessible, such as one in 60 the toe portion, may be placed over the arm with the cutting block in position to support the panel from the inside of the shoe; and then the shoe may be moved over the 65 arm and turned in one direction or the other with the arm, and both may be turned completely around if desired.

In machines of this kind, it is desirable that a shearing cut be employed. According to another feature of the invention, the 70 cutting block has a curved shearing edge the curvature of which is concentric relatively to the axis about which the carrier swings. The cutting block and its shearing edge are 75 preferably annular to provide for the maintenance of a cooperative shearing relation with the cutter irrespective of how far the cutting block is turned about its axis. As illustrated, the cutter is operated by reciprocation lengthwise of said axis and its cutting 80 edge is curved to conform to the inner edge of the annular shear member with which it cooperates. A relatively slender pilot portion formed on the cutter projects in advance of its cutting edge to pierce the work prior to the trimming operation and to maintain continual contact between the cutter and the inner edge of the annular shear member during the trimming operation. This continual 85 contact insures guiding the cutting edge of the cutter in the desired cooperative relation to the annular shear member irrespective of rotary motion of the latter and irrespective of any stress tending to deflect the cutter laterally out of register with the annular member. 90

These and other features of the invention, including certain details of construction and combinations of parts, will be described as embodied in an illustrative machine and pointed 95 out in the appended claims.

Referring now to the accompanying drawings,

Figure 1 is a perspective of a machine in which the present invention is embodied; 100

Figure 2 is an elevation of a shoe showing the sort of work the machine is designed to perform;

Figure 3 is a detail in elevation of a portion of the knee-lever mechanism;

Figure 4 is an end elevation of the machine with a cover plate removed and a small portion of the machine in section;

Figure 5 is a detail in section showing a piece of work in process of being operated upon;

Figure 6 is a plan of the parts of the machine shown in Figure 5, the cutter and the combined cutter guard and edge gage being shown in section; and

Figure 7 is a perspective on an enlarged scale of the combined cutter guard and edge gage.

Referring first to Figures 4, 5 and 6, the general mode of operation of the machine will be briefly described. The machine comprises a reciprocating cutter 9 having a pointed pilot portion 11 and a narrow cutting edge 13 at one face of the cutter which is curved, as shown in Figure 6, to conform to the curvature of the inner wall of an annular shear member 15 or cutting block arranged to support the work. A combined cutter guard and edge gage 17 has a curved face which is in contact with a curved face of the cutter, a depending lip 21 which acts as a gage, and a flange 23 which is located in front of the cutter to prevent injury to the fingers of the operator. The cutting block or shear member 15 is carried by one end of a substantially horizontal arm 25 which is rotatable about a vertical axis coincident with the center of curvature of the shear member. With this construction it will be clear that the cooperative cutting relation of the cutter and the shear member will be maintained in any position to which the arm may be swung.

Referring now more particularly to Figure 5, there is shown a portion 100 of the upper of a shoe having an ornamental opening 200 therein across which extends the lining 300, the upper and lining being fastened together along the edge of the opening by a row of stitches 400.

In the operation of the machine, the cutter 9 and guard 17 are first raised manually to permit a shoe to be placed over the arm 25 with the shear member 15 supporting the desired locality of the shoe from the inside thereof. The cutter and guard are then lowered manually to the positions shown in Figure 5, the pointed portion of the cutter, during this descent, acting to pierce the panel so as to start the cut. Immediately upon the completion of this descent the automatic reciprocation of the cutter begins, but the pilot portion 11 remains in contact with the shear member 15 throughout the range of automatic reciprocation to insure accurate cooperation of the cutting edge 13 and the member 15. The shoe is then fed by the operator in such manner as to cause that

portion of the lining which extends across the ornamental opening 200 in the upper 100 to be cut out progressively. During this feeding the shoe may be moved as desired with respect to the supporting arm and may be swung to any desired extent—completely around if necessary—by reason of the mounting of the arm. It is thus possible to cut out panels irrespective of their outlines and locations.

The cutter 9 is fastened to a block 29 by screws 27 in such manner that the cutter may be adjusted vertically; and the block is in turn fastened by a screw 31 to the lower end of a cutter-bar 33 in such manner that it may be adjustably laterally. The cutter-bar is vertically slidable in alined bearings formed in the head 35 of the machine frame and in a boss 135 affixed to the head, said head being a part of an overhanging arm 37 of the frame which includes a column 39. The upper end of the cutter-bar 33 is held by a pinch-screw 41 in a pinch-block 43 which is pivotally connected through a short link 45 with the outer end of an arm 47, the inner end of said arm being loosely pivoted on a stud 49. Also loosely pivoted on the stud 49 is the inner end of a second arm 51, the outer end of which is pivoted at 53 to a short link 55 the lower end of which has an opening to receive a crank-pin 57 on the end of a driving shaft 59, a ball bearing 61 being located between the crank-pin and the link 55. When, therefore, the shaft 59 is rotated, the arm 51 is swung up and down about the stud 49. In order to transmit this movement, when desired, to the arm 47 and thence to the cutter 9, as well as to permit the cutter to be raised at any time and brought to rest in raised position, the lower arm 47 has a lug 62 with the under face of which the upper face of a lug 63 formed at the lower end of a depending portion of the upper arm 51 is adapted to contact. A spring 65 coiled about the stud 49 has one of its free ends engaging the under side of the upper arm 51 and the other free end engaging the upper side of the lower arm 47. This spring thus tends at all times to swing the arms apart about the stud 49. In order normally to hold them in the relative positions shown so that rotation of the driving shaft 59 will cause reciprocation of the cutter-bar 33, a latch 67 pivoted at 69 to the lower arm extends beneath the lug 63 of the upper arm, said latch being urged at all times to swing in a clockwise direction by a spring 71 which extends from beneath the lower arm 47, around the pilot 69 and up over the tail of the latch. When, now, the shaft 59 is rotated, the upper arm 51 is oscillated about the stud 49, and the same oscillation is imparted to the lower arm 47, since the arms are positively held from angular movement with respect to each other. The outer end of the

100

115
120
125
130

lower arm is connected with the cutter-bar in the manner which has been described, and consequently the cutter is reciprocated.

In order to provide for tripping the latch 5 and raising the arm 47 when desired, and thus raising the cutter and bringing it to rest, a rod 73 slidably in vertically alined bearings has its upper end located beneath the tail of the latch and has extending from one side 10 thereof and beneath the lower arm 47 a pin 75. When, therefore, the rod 73 is pushed upwardly, its upper end first disengages the latch and then the pin 75 raises the arm 47 against the force of the spring 65. The 15 cutter is thus disconnected from its driving mechanism and held raised well above the work support. The cutter is thus raised and brought to rest whenever it is desired to start the cutting out of a panel, the cutter being 20 raised sufficiently to bring its pointed portion 11 well above the level of the work support so that the shoe may be moved to bring a fresh panel into place to be pierced by said pointed portion when the cutter makes its first downward movement. This downward movement occurs as soon as the rod 73 is permitted to descend. At that time the spring 25 65 swings the lower arm 47 downwardly as far as the lugs 61, 63 will permit; and the 30 spring 71 causes the latch 67 to engage once more the under side of the lug 63. The arms 47, 51 are thus once more held from angular movement with respect to each other and the cutter is reciprocated. If desired, a tension 35 spring 77 may be connected at its upper end to the lower arm 47 and at its lower end to the head of the machine to supplement the action of the spring 65. Such additional spring is particularly advantageous when a 40 panel composed of thick, tough leather is to be pierced.

The rod 73 is raised, for the purpose which has just been described, by means of a lever 79 pivoted at 81 to the overhanging arm 37 45 and having pivoted to its outer end a treadle rod 83 to the lower end of which a treadle (not shown) is connected. The operative end of the lever 79 carries a screw 85 the head of which contacts with the under side of a pin 50 87 carried by the rod 73. A tension spring 88 connects the pin with the lever.

As has been briefly explained, there is associated with the cutter a combined guard and gage 17 having a depending lip 21 which 55 engages the edge of the ornamental opening in the upper. This combined member serves both to facilitate the guiding of the shoe and to prevent accidental injury both to the upper and to the fingers of the operator. Referring 60 more particularly to Figures 5, 6 and 7, this member has a vertical face 21 to engage the edge of the opening in the upper, a horizontal face 89 to rest upon the margin of the upper about the ornamental opening, and 65 a flange 23 extending in front of the cutter.

When the cutter is raised preparatory to piercing a panel, the combined guard and gage 17 is raised with it by reason of the contact of the outer end of the screw 81 with a lug 91 projecting from a collar 93 carried by the rod 95 to the lower end of which the combined guard and gage is fastened by a screw 97. During the cutting operation, the combined member occupies the position shown best in Figure 5.

In order to hold it in that position and to permit it to be raised independently of the cutter so as to pass readily over a relatively thick portion 700 of the lining, such as a seam, the rod 95 (Fig. 4) has fastened to its upper end a bar 98 upon the upper side of which a spring-pressed plunger 99 bears, downward movement of the rod being limited by a stop-screw 101 which engages the under side of the bar 98. Also engaging the under side of the bar 98 is a lifting lever 103 pivoted at 80 81 to the overhanging arm and connected at its inner end to the upper end of a sectional pull-rod 105, the lower end of which is pivoted to a bell-crank lever 107 pivoted in turn at 90 109 to a bracket 111 fast to the pedestal 39, said bell-crank lever being urged at all times by a spring 110 to rotate in a clockwise direction as far as an adjustable stop-screw 113 will permit. Extending 95 downwardly from the bell-crank lever is a rod 115 to the lower end of which is fastened a knee-piece 117 arranged to be moved by the knee of the operator. An adjustable stop-screw 119 determines the extent to which the bell-crank lever 107 may be rocked. The two sections of the rod 105 are adjustably fastened together by a clamp 121. During the cutting operation, the lower edge of the lip 21 of the combined guard and gage 17 should be in 100 contact with the lining 300; and when a seam such as that represented at 700 is about to pass under the lip 21 its passage will be facilitated by lifting the member 17 but the latter should not be raised so far as to disengage the lip 21 from the edge of the ornamental opening in the upper. The stop-screw 101, which determines the lower limit of movement of the combined member, and the stop-screw 119, which determines its upper limit, may be 105 adjusted accordingly. When a seam in the lining is encountered, therefore, the operator has merely to operate the knee-lever mechanism in order to raise the combined guard and gage into the proper position.

As has been explained above, the arm 25 is rotatable about an axis passing through the axis of curvature of the shear member 15. In the illustrative machine, this shear member is detachably clamped in the arm 25, the latter being at the lower end and a part of a pendent, U-shaped work-support 125. The arm 25 is thus arranged to project into a hollow article of work such as a shoe, and since 120 all the rest of the work-support is above the 125

level of the arm 25 a clear, unobstructed space is provided below said arm to receive the body of a hollow article of work and to provide for unrestricted manipulation thereof. A swivel connection between the work-support 125 and the overhanging arm 37 of the frame is provided by a cylindric boss 135 affixed to and projecting downwardly from said arm. This boss not only extends 10 through a hub formed on the pendent work-support 125 but also provides bearings through which the cutter-bar 33 and the gage-rod 95 extend. If desired, the swivel connection between the work-support 125 15 and the boss 135 may include ball-bearings 137 held intact by a nut 139 applied to the lower end of said boss.

Since many cutting strokes of the cutter 9 are necessary to sever completely the panel 20 of waste material, and since the work must be fed meanwhile, it is desirable to fend the panel from entering the hole in the shear member 15. Accordingly a fender 141 is arranged in the hole of the member 15 so that 25 its work-engaging surface will lie substantially flush with the plane of the shearing edge of said member. The fender is smaller than the hole in the member 15 to provide a space into which the cutter 9 may enter, and 30 is preferably mounted to exert pressure against the cutter, transversely of the hole, to insure shearing relation of the cutter and the shear member 15. For these purposes the fender is formed with a stem that extends 35 loosely through a hole in a support 143 so that it may tip from side to side, and a compression spring 149 is arranged on the stem to hold the fender normally in substantially coaxial relation to the hole. Nuts 145 and 147 40 screwed on the stem cooperate with the spring to produce the effects mentioned above. The support 143 is affixed to the arm 25.

In operation, the point of the cutter 9, as 45 it enters the hole in the shear member 15, deflects the fender laterally, and the reaction of the spring 149 maintains lateral pressure of the fender against the cutter. In the event that the point of the cutter fouls the fender 50 the spring permits the latter to yield axially to avoid breaking the cutter, and in the course of one or two strokes of the cutter the fender is deflected and takes the position shown by Figs. 5 and 6. The operation of the cutter 55 produces vibration of the fender which facilitates the passage of the waste material over the shear member 15.

Referring now to Figure 2, there is shown a shoe having ornamental openings in the upper 100 thereof. As viewed from the side, 60 there is a large opening 500 and three small openings 600. In the particular shoe shown, the lining extends entirely across the openings 600 but only partly across the opening 500, but the operation of cutting out the lining is substantially the same in both cases.

Considering first the operation of the machine with respect to the opening 500, the treadle (not shown) which is attached to the lower end of the treadle rod 83, is depressed to raise the cutter 9, and with it the guard 17, 70 well above the cutting block 15, it being understood that the extent to which these members are raised is sufficient to permit the upper and lining of the shoe to pass beneath them as the shoe is slipped over the arm 25. 75 The treadle is then released to cause the cutter and guard to descend to the positions shown in Figure 5. Thereafter the shoe is fed manually over the arm 25 in such manner as to cause the lining to be cut out. When a seam such as that indicated at 700 is encountered, the knee lever 117 is manipulated to raise the guard 17 slightly. It should be particularly noted that to trim entirely around an opening requires turning the shoe about a vertical axis through a range sometimes 360 degrees and that the rotary mounting of the carrier 125 provides for unlimited turning movement. The operation upon the lining beneath the openings 600 is like that which has been described above except that in the first downward movement of the cutter, after the shoe is in place, the pointed portion 11 of the cutter pierces the panel.

Although the invention has been set forth as embodied in a particular machine and in connection with a certain kind of work, it should be understood that the invention is not limited in the scope of its application to the particular machine, nor to operation upon the particular kind of work which has been shown and described.

Having thus described my invention, what I claim as new and desire to secure by Letters Patent of the United States is:—

1. A trimming machine comprising a cutter and a work-support movable relatively one to the other lengthwise of an axis and about said axis, and mechanism for relatively reciprocating them lengthwise of said axis, said cutter and said work-support having portions arranged to maintain contact of one with the other irrespective of their relative movements.

2. A trimming machine comprising means provided with a shearing edge arranged to support any selected portion of the upper of a shoe internally, a reciprocatory cutter arranged to cooperate with said shearing edge to sever a portion of the upper, mechanism for operating said cutter, said means being movable relatively to said cutter about an axis intersecting the work adjacent to the cutting locality, and means operable at will to separate said cutter and the work-engaging portion of said work-supporting means.

3. A trimming machine comprising a work-supporting arm arranged to project into a shoe to support any selected portion of the upper internally, a reciprocatory cut-

ter and mechanism for operating it to cut against said arm, and a cutter-guard having a face arranged to guide the work by engagement with an edge thereof, said arm being movable relatively to said cutter and cutter-guard about an axis intersecting the work supported thereby.

4. A trimming machine comprising a reciprocatory trimming cutter and mechanism for imparting operative motion thereto, a work-supporting arm arranged to project into a shoe, and a work-engaging element arranged on said arm to sustain a portion of the upper of the shoe against the cutting stress of said cutter, said work-supporting arm being arranged to turn relatively to said cutter about an axis intersecting said work-engaging element, and said cutter and work-engaging element having shearing edges arranged to cooperate with each other.

5. A trimming machine comprising a reciprocatory cutter and mechanism for operating it, and work-supporting means including an arm arranged to project into a shoe and a cutting block against which said cutter operates, said means being movable relatively to said cutter about an axis intersecting said cutting block, and said cutter and cutting block having cooperative curved shearing edges the curvature of which is concentric to said axis.

6. A machine of the class described having, in combination, a member adapted to support selected portions of the upper of a shoe by engagement with the lining thereof, a cutter arranged to cooperate with the member, a combined cutter guard and edge gage adapted to shield the cutter and to facilitate the guiding of the shoe, and means for operating the cutter, said member being angularly movable about an axis which extends through a point in the vicinity of the locality in which the cutting takes place to permit a cut of endless outline to be made.

45. 7. A trimming machine comprising a work-support arranged to turn about an axis intersecting the work arranged thereon, a trimming cutter arranged to cut against said work support, and mechanism arranged to reciprocate said cutter lengthwise of said axis, said cutter having a portion arranged to remain in contact with said work-support throughout the range of reciprocation imparted by said mechanism.

55. 8. A trimming machine comprising a reciprocatory cutter-bar and a cutter carried thereby, a boss in which said cutter-bar is arranged to slide, mechanism for operating said cutter-bar, a work-support having a hub surrounding and supported by said boss, said work-support being adapted to turn about said boss and being shaped to project into the forepart of a shoe while said cutter is operating on the exterior of the forepart of

the upper, and a cutting block arranged on 65 said work-support to support the upper by engagement with the lining thereof.

9. A trimming machine comprising a boss, a rotatable work-support having a hub surrounding and supported by said boss, said work-support being formed to project into the forepart of a shoe and having a cutting block arranged to support the upper of the forepart by engagement with the lining thereof, two bars extending through said boss and said hub, a cutter affixed to one of said bars in cooperative relation to said cutting block, mechanism for reciprocating said cutter-bar, a work-gage carried by the other one of said bars, and means for shifting said 80 gage-bar to retract the gage from the work.

10. A trimming machine comprising a work-support having a hub and a laterally offset arm the outer end of which is coaxial with the hub and formed to project into the 85 forepart of a shoe and support the latter by engagement with the lining of the upper, a supporting structure relatively to which said work-support is rotatable and to which said hub is secured, and trimming mechanism including a reciprocatory cutter extending through said hub and arranged to cut against the outer end of said work-support.

11. A machine of the class described having, in combination, a work-support having an arm shaped to enter a shoe, a cutting block carried by the arm to engage the inside of the shoe upper, a reciprocating cutter arranged to operate against the block first to pierce the shoe and then to cut a piece from it, a gage arranged to position the shoe by engagement with an edge of the upper, and means for raising the cutter above the shoe preparatory to the piercing operation, said work-support being arranged to turn relatively to said cutter and said edge gage about an axis parallel to the plane of the cut.

12. A machine of the class described having, in combination, a shear member adapted to be held against the inside of the upper of a shoe, a reciprocatory cutter arranged to cooperate with said shear member, and a rotatable support adapted to project into a shoe to maintain said shear member in cooperative relation to said cutter.

13. A machine of the class described having, in combination, a shear member adapted to be held against the inside of the upper of a shoe, a cooperating cutter, an edge gage adapted to facilitate the guiding of the shoe, and means by which said shear member is maintained in cooperative relation to said cutter and said edge gage, said means being arranged to turn relatively to said cutter and edge gage about an axis parallel to the plane of the shearing cut.

14. A machine of the class described having, in combination, an arm shaped to enter

a shoe, a shear member carried by the arm, a cutter arranged to cooperate with the shear member, and means for operating the cutter, said arm being mounted for swinging movement in such manner that the cooperative relation of the cutter and shear member is maintained in the various positions of the arm.

15. A machine of the class described having, in combination, an arm shaped to enter a shoe, a shear member carried by the arm, a cutter arranged to cooperate with the shear member, a combined cutter guard and edge gage adapted to shield the cutter and to facilitate the guiding of the shoe, and means for operating the cutter, said arm being mounted for swinging movement in such manner that the cooperative relation of the cutter and shear member is maintained in the various positions of the arm.

16. A machine of the class described having, in combination, an arm shaped to enter a shoe, a shear member carried by the arm, a cutter arranged to cooperate with the shear member, and means for reciprocating the cutter, said arm being mounted for swinging movement about an axis which is substantially parallel to the path of reciprocation of the cutter.

17. A trimming machine comprising a shear member and a reciprocatory cutter arranged to cooperate in shearing relation, one inside and the other outside the forepart of a shoe, to sever lining panels from the upper, an arm mounted for swinging movement and arranged to extend into the shoe to support one of said severing members inside the latter, means for initially separating said severing members to permit placing a panel between them without cutting any part of the shoe, and mechanism for operating said cutter.

18. A machine of the class described having, in combination, a reciprocating cutter and a cooperating shear member curved in cross-section, and means supporting said member so that it may turn about the axis of curvature.

19. A machine of the class described having, in combination, a reciprocating cutter, a hollow shear member with the inside edge of which the cutter cooperates, and means to support one of said elements inside a shoe.

20. A machine of the class described having, in combination a reciprocating cutter, and a shear member having complementally curved shearing edges, and an arm for supporting said shear member, said arm being mounted to swing about the axis of curvature of said edges.

21. A machine of the class described having, in combination, a reciprocating cutter, a cooperating shear member having a curved edge, and an arm by which the shear member is carried, said arm being mounted for swinging movement about an axis which contains

substantially the center of curvature of the curved edge.

22. A machine of the class described having, in combination, a shear member circular in cross-section and adapted to be held against the inside of the upper of a shoe, a reciprocating cutter arranged to cooperate with a curved edge of the shear member, and a carrier for said shear member angularly movable about an axis passing substantially through the axis of curvature of said member.

23. A machine of the class described having, in combination, a shear member circular in cross-section and adapted to be held against the inside of the upper of a shoe, a reciprocating cutter arranged to cooperate with a curved edge of the shear member, and a carrier for said shear member angularly movable about an axis passing substantially through the axis of curvature of said member, one face of the cutter being curved in cross-section to correspond to the cross-sectional curvature of the shear member.

24. A machine of the class described comprising a supporting arm mounted for swinging movement and arranged to project into a shoe, two cooperative shearing members one of which is supported by said arm, means for supporting the other one of said members, mechanism for reciprocating one of said shearing members, the latter one of said members having a cutting edge and a point projecting therefrom to pierce the work, and means for retracting said latter one beyond the range of reciprocation afforded by said mechanism to facilitate placing the work.

25. A machine of the class described having, in combination, an arm shaped to enter a shoe, a hollow cutting block having a shearing edge, a cooperating reciprocating cutter having a shearing edge and a pointed portion adapted to pierce the shoe, and means for raising the pointed portion of the cutter above the shoe preparatory to the piercing operation, said arm being mounted for swinging movement to permit the shoe to be turned freely at any time.

26. A machine of the class described having, in combination, an arm, a hollow shear member carried by the arm, a cutter arranged to cooperate with the inner edge of the hollow member, and means for reciprocating the cutter, said arm being angularly movable about an axis passing substantially through the axis of curvature of the inner edge of said shear member.

27. A machine for cutting a panel from the toe portion of the upper of a shoe having, in combination, an arm arranged to extend into a shoe, a shear member circular in cross-section carried near the end thereof, a cutter having a curved shearing edge arranged to cooperate with said shear member, means for reciprocating the cutter, and means supporting the arm so that it may

swing about the axis of curvature of said edges to permit the shoe to be turned so as to sever the panel completely.

28. A machine for cutting a panel from the toe portion of the upper of a shoe having, in combination, an arm arranged to extend into a shoe, a shear member carried near the end thereof and having a circular internal shearing edge, a cutter having a curved cutting edge arranged to cooperate with said circular edge, means for reciprocating the cutter, and means supporting the arm so that it may be swung from side to side or completely around so that it offers no obstruction to the swinging of the shoe in cutting from the lining thereof the entire panel.

29. A machine of the class described having, in combination, a reciprocating cutter having a curved face, a cooperating shear member having a curved edge the curvature of which corresponds to that of the curved face of the cutter, and an arm by which the shear member is carried, said arm being mounted for swinging movement about an axis which contains substantially the center of curvature of the face of the cutter and the edge of the shear member.

30. A machine for trimming the lining which projects beyond an edge of the upper of a shoe having, in combination, a shear member adapted to support a portion of the superposed lining and upper, a reciprocating cutter adapted to sever the lining, a gage adapted to contact with the edge of the upper, yielding means acting normally to hold the gage in light contact with a single thickness of the lining, a knee lever for raising the gage so as to permit a thickened portion of the lining such as a seam to pass beneath it, and a stop to prevent the gage from being raised above the level of the edge of the upper.

31. A machine of the class described comprising a hollow shear member, a reciprocatory cutter arranged to cooperate with said member in the hole thereof, said hole being larger than said cutter, and means arranged in said hole to exert lateral pressure against said cutter and thereby insure shearing relation of said cutter and said shear member.

32. A machine of the class described comprising a hollow shear member, a spring-stressed member arranged in the hole in said shear member to yield lengthwise and transversely of said hole, and a reciprocatory cutter arranged to enter said hole, deflect said spring-stressed member transversely from its normal position and cooperate with said shear member, said spring-stressed member being effective to insure shearing relation of said cutter and said shear member and to fend the work from said hole.

33. A machine of the class described having, in combination, a shear member having a cylindrical opening therein, a cylindrical plunger of smaller diameter than the open-

ing located in said opening, yielding means tending at all times to hold the plunger concentric to the opening, a narrow cutter having a tapered end extending between the plunger and the wall of the opening, and means for reciprocating the cutter and thereby vibrating the plunger.

34. A machine of the class described having, in combination, a shear member having a cylindrical opening therethrough, a plunger of smaller diameter than the upper part of the opening located in the opening, a support for the plunger located beneath the opening and provided with a hole to receive loosely the stem of the plunger, and a coiled spring located between the plunger and the support.

35. A machine of the class described having, in combination, a shear member, a cutter arranged to cooperate therewith, and a combined cutter guard and edge gage located close to the cutter and having a portion arranged to guide an edge of the work, a portion arranged to cover the cutter, and a surface arranged to rest upon the margin of the work adjacent to said guiding portion.

36. A machine of the class described having, in combination, a frame having an overhanging arm provided with a downward extension, a generally U-shaped carrier having a stem rotatably mounted upon said extension a cutting block mounted near the extremity of the lower arm of the U-shaped carrier, a cutter adapted to cooperate with the block, and means for reciprocating the cutter.

37. A machine of the class described having, in combination, a frame having an overhanging arm provided with a downward extension, a generally U-shaped carrier having a stem rotatably mounted upon said extension, a cutting block curved in cross-section mounted near the extremity of the lower arm of the U-shaped carrier, a cutter adapted to cooperate with the block, and members for reciprocating the cutter.

38. A machine of the class described having, in combination, a reciprocating cutter, a cutting block, a generally U-shaped carrier near the end of one arm of which the block is carried, said arm being shaped to enter a shoe, and means for rotatably mounting the carrier, there being a free and unobstructed space about the carrier to permit the shoe and carrier to be swung as may be desired.

39. A machine of the class described having, in combination, a member arranged to project into a shoe to support the latter internally, a cutting member arranged to cooperate with said supporting member, and means for operating the cutting member, said supporting member being arranged to turn with the shoe but to remain in cooperative relation to said cutting member.

40. A trimming machine comprising a

shear member, a reciprocatory knife arranged to cooperate therewith, said knife having a pilot, and a guide arranged to engage said knife adjacent to the point of cut to maintain the knife in contact with the shear member.

5 41. A trimming machine comprising a supporting arm arranged to project into the forepart of a shoe, a shear member and a guide both supported by said arm to function inside the shoe, and a reciprocatory knife arranged to operate between said guide and said shear member, said guide being arranged to maintain said knife in shearing relation to said shear member and to sustain the severed 10 material against the drag of the knife toward the interior of the shoe.

42. A machine of the class described comprising a stationary overhanging frame element and a pendent work-support having 15 a swivel connection whereby said work-support is adapted to be turned about a vertical axis, said work-support having a laterally extending portion at its lower end formed and arranged to project into a hollow article 20 of work to engage the latter adjacent to said axis and to provide a clear unobstructed space for the body of such article, a bar extending vertically through said frame element and having a tool at its lower end arranged to operate on the article of work adjacent to said axis, and mechanism arranged to impart 25 vertical reciprocatory operating motion to said bar.

43. A machine of the class described comprising a stationary overhanging frame element and a pendent work-support having a 30 swivel connection whereby said work-sup-

port is adapted to be turned about a vertical axis, said work-support having a laterally extending portion at its lower end formed 40 and arranged to project into the forepart of a shoe to engage a portion of the latter adjacent to said axis, a bar extending vertically through said frame element and having a cutter at its lower end arranged to cooperate 45 with said laterally extending portion adjacent to said axis to sever a panel of the shoe lining, and mechanism arranged to impart vertical reciprocatory cutting motion to said bar.

44. A machine of the class described comprising a stationary overhanging frame element and a pendent work-support having a swivel connection whereby said work-support is adapted to be turned about a vertical axis, 55 said work-support having a laterally extending portion at its lower end formed and arranged to project into the upper of a shoe, a cutting block affixed to said laterally extending portion and having a circular internal 60 shearing edge surrounding said axis, a bar extending vertically through said frame element, mechanism arranged to reciprocate said bar vertically, a cutter carried by said bar and arranged to cooperate with said shearing edge to trim progressively lining material projecting beyond a finished edge of the upper, and a gage arranged to run on such finished edge to guide it close to but clear of 65 said cutter.

In testimony whereof I have signed my name to this specification.

GEORGE BOULTON.

DISCLAIMER

1,700,624.—*George Boulton*, Rochester, N. Y. LINING-TRIMMING MACHINE. Patent dated January 29, 1929. Disclaimer filed March 9, 1931, by the assignee, *United Shoe Machinery Corporation*.

Hereby presents this disclaimer to said claims 1, 2, 3, 4, 5, 6, 7, 11, 12, 13, 14, 15, 16, 17, 18, 19, 20, 21, 22, 23, 24, 25, 26, 27, 28, 29, 32, 33, 34, 38, 39, and 41 of said patent which are in the following words, to wit:

“1. A trimming machine comprising a cutter and a work-support movable relatively one to the other lengthwise of an axis and about said axis, and mechanism for relatively reciprocating them lengthwise of said axis, said cutter and said work-support having portions arranged to maintain contact of one with the other irrespective of their relative movements.

“2. A trimming machine comprising means provided with a shearing edge arranged to support any selected portion of the upper of a shoe internally, a reciprocatory cutter arranged to cooperate with said shearing edge to sever a portion of the upper, mechanism for operating said cutter, said means being movable relatively to said cutter about an axis intersecting the work adjacent to the cutting locality, and means operable at will to separate said cutter and the work-engaging portion of said work-supporting means.

“3. A trimming machine comprising a work-supporting arm arranged to project into a shoe to support any selected portion of the upper internally, a reciprocatory cutter and mechanism for operating it to cut against said arm, and a cutter-guard having a face arranged to guide the work by engagement with an edge thereof, said arm being movable relatively to said cutter and cutter-guard about an axis intersecting the work supported thereby.

“4. A trimming machine comprising a reciprocatory trimming cutter and mechanism for imparting operative motion thereto, a work-supporting arm arranged to project into a shoe, and a work-engaging element arranged on said arm to sustain a portion of the upper of the shoe against the cutting stress of said cutter, said work-supporting arm being arranged to turn relatively to said cutter about an axis intersecting said work-engaging element, and said cutter and work-engaging element having shearing edges arranged to cooperate with each other.

“5. A trimming machine comprising a reciprocatory cutter and mechanism for operating it, and work-supporting means including an arm arranged to project into a shoe and a cutting block against which said cutter operates, said means being movable relatively to said cutter about an axis intersecting said cutting block, and said cutter and cutting block having cooperative curved shearing edges the curvature of which is concentric to said axis.

“6. A machine of the class described having, in combination, a member adapted to support selected portions of the upper of a shoe by engagement with the lining thereof, a cutter arranged to cooperate with the member, a combined cutter guard and edge gage adapted to shield the cutter and to facilitate the guiding of the shoe, and means for operating the cutter, said member being angularly movable about an axis which extends through a point in the vicinity of the locality in which the cutting takes place to permit a cut of endless outline to be made.

“7. A trimming machine comprising a work-support arranged to turn about an axis intersecting the work arranged thereon, a trimming cutter arranged to cut against said work support, and mechanism arranged to reciprocate said cutter lengthwise of said axis, said cutter having a portion arranged to remain in contact with said work-support throughout the range of reciprocation imparted by said mechanism.”

“11. A machine of the class described having, in combination, a work-support having an arm shaped to enter a shoe, a cutting block carried by the arm to engage the inside of the shoe upper, a reciprocating cutter arranged to operate against the block first to pierce the shoe and then to cut a piece from it, a gage arranged to position the shoe by engagement with an edge of the upper, and means for raising the cutter above the shoe preparatory to the piercing operation, said work-support being arranged to turn relatively to said cutter and said edge gage about an axis parallel to the plane of the cut.

“12. A machine of the class described having, in combination, a shear member adapted to be held against the inside of the upper of a shoe, a reciprocatory cutter arranged to cooperate with said shear member, and a rotatable support adapted to project into a shoe to maintain said shear member in cooperative relation to said cutter.

“13. A machine of the class described having, in combination, a shear member adapted to be held against the inside of the upper of a shoe, a cooperating cutter, an

edge gage adapted to facilitate the guiding of the shoe, and means by which said shear member is maintained in cooperative relation to said cutter and said edge gage, said means being arranged to turn relatively to said cutter and edge gage about an axis parallel to the plane of the shearing cut.

"14. A machine of the class described having, in combination, an arm shaped to enter a shoe, a shear member carried by the arm, a cutter arranged to cooperate with the shear member, and means for operating the cutter, said arm being mounted for swinging movement in such manner that the cooperative relation of the cutter and shear member is maintained in the various positions of the arm.

"15. A machine of the class described having, in combination, an arm shaped to enter a shoe, a shear member carried by the arm, a cutter arranged to cooperate with the shear member, a combined cutter guard and edge gage adapted to shield the cutter and to facilitate the guiding of the shoe, and means for operating the cutter, said arm being mounted for swinging movement in such manner that the cooperative relation of the cutter and shear member is maintained in the various positions of the arm.

"16. A machine of the class described having, in combination, an arm shaped to enter a shoe, a shear member carried by the arm, a cutter arranged to cooperate with the shear member, and means for reciprocating the cutter, said arm being mounted for swinging movement about an axis which is substantially parallel to the path of reciprocation of the cutter.

"17. A trimming machine comprising a shear member and a reciprocating cutter arranged to cooperate in shearing relation, one inside and the other outside the fore-part of a shoe, to sever lining panels from the upper, an arm mounted for swinging movement and arranged to extend into the shoe to support one of said severing members inside the latter, means for initially separating said severing members to permit placing a panel between them without cutting any part of the shoe, and mechanism for operating said cutter.

"18. A machine of the class described having, in combination, a reciprocating cutter and a cooperating shear member curved in cross-section, and means supporting said member so that it may turn about the axis of curvature.

"19. A machine of the class described having, in combination, a reciprocating cutter, a hollow shear member with the inside edge of which the cutter cooperates, and means to support one of said elements inside a shoe.

"20. A machine of the class described having, in combination, a reciprocating cutter, and a shear member having complementally curved shearing edges, and an arm for supporting said shear member, said arm being mounted to swing about the axis of curvature of said edges.

"21. A machine of the class described having, in combination, a reciprocating cutter, a cooperating shear member having a curved edge, and an arm by which the shear member is carried, said arm being mounted for swinging movement about an axis which contains substantially the center of curvature of the curved edge.

"22. A machine of the class described having, in combination, a shear member circular in cross-section and adapted to be held against the inside of the upper of a shoe, a reciprocating cutter arranged to cooperate with a curved edge of the shear member, and a carrier for said shear member angularly movable about an axis passing substantially through the axis of curvature of said member.

"23. A machine of the class described having, in combination, a shear member circular in cross-section and adapted to be held against the inside of the upper of a shoe, a reciprocating cutter arranged to cooperate with a curved edge of the shear member, and a carrier for said shear member angularly movable about an axis passing substantially through the axis of curvature of said member, one face of the cutter being curved in cross-section to correspond to the cross-sectional curvature of the shear member.

"24. A machine of the class described comprising a supporting arm mounted for swinging movement and arranged to project into a shoe, two cooperative shearing members one of which is supported by said arm, means for supporting the other one of said members, mechanism for reciprocating one of said shearing members, the latter one of said members having a cutting edge and a point projecting therefrom to pierce the work, and means for retracting said latter one beyond the range of reciprocation afforded by said mechanism to facilitate placing the work.

"25. A machine of the class described having, in combination, an arm shaped to enter a shoe, a hollow cutting block having a shearing edge, a cooperating reciprocating cutter having a shearing edge and a pointed portion adapted to pierce the shoe,

and means for raising the pointed portion of the cutter above the shoe preparatory to the piercing operation, said arm being mounted for swinging movement to permit the shoe to be turned freely at any time.

"26. A machine of the class described having, in combination, an arm, a hollow shear member carried by the arm, a cutter arranged to cooperate with the inner edge of the hollow member, and means for reciprocating the cutter, said arm being angularly movable about an axis passing substantially through the axis of curvature of the inner edge of said shear member.

"27. A machine for cutting a panel from the toe portion of the upper of a shoe having, in combination, an arm arranged to extend into a shoe, a shear member circular in cross-section carried near the end thereof, a cutter having a curved shearing edge arranged to cooperate with said shear member, means for reciprocating the cutter, and means supporting the arm so that it may swing about the axis of curvature of said edges to permit the shoe to be turned so as to sever the panel completely.

"28. A machine for cutting a panel from the toe portion of the upper of a shoe having, in combination, an arm arranged to extend into a shoe, a shear member carried near the end thereof and having a circular internal shearing edge, a cutter having a curved cutting edge arranged to cooperate with said circular edge, means for reciprocating the cutter, and means supporting the arm so that it may be swung from side to side or completely around so that it offers no obstruction to the swinging of the shoe in cutting from the lining thereof the entire panel.

"29. A machine of the class described having, in combination, a reciprocating cutter having a curved face, a cooperating shear member having a curved edge the curvature of which corresponds to that of the curved face of the cutter, and an arm by which the shear member is carried, said arm being mounted for swinging movement about an axis which contains substantially the center of curvature of the face of the cutter and the edge of the shear member."

"32. A machine of the class described comprising a hollow shear member, a spring-stressed member arranged in the hole in said shear member to yield lengthwise and transversely of said hole, and a reciprocatory cutter arranged to enter said hole, deflect said spring-stressed member transversely from its normal position and cooperate with said shear member, said spring-stressed member being effective to insure shearing relation of said cutter and said shear member and to fend the work from said hole.

"33. A machine of the class described having, in combination, a shear member having a cylindrical opening therein, a cylindrical plunger of smaller diameter than the opening located in said opening, yielding means tending at all times to hold the plunger concentric to the opening, a narrow cutter having a tapered end, extending between the plunger and the wall of the opening, and means for reciprocating the cutter and thereby vibrating the plunger.

"34. A machine of the class described having, in combination, a shear member having a cylindrical opening therethrough, a plunger of smaller diameter than the upper part of the opening located in the opening, a support for the plunger located beneath the opening and provided with a hole to receive loosely the stem of the plunger, and a coiled spring located between the plunger and the support."

"38. A machine of the class described having, in combination, a reciprocating cutter, a cutting block, a general U-shaped carrier near the end of one arm of which the block is carried, said arm being shaped to enter a shoe, and means for rotatably mounting the carrier, there being a free and unobstructed space about the carrier to permit the shoe and carrier to be swung as may be desired.

"39. A machine of the class described having, in combination, a member arranged to project into a shoe to support the latter internally, a cutting member arranged to cooperate with said supporting member, and means for operating the cutting member, said supporting member being arranged to turn with the shoe but to remain in cooperative relation to said cutting member."

"41. A trimming machine comprising a supporting arm arranged to project into the forepart of a shoe, a shear member and a guide both supported by said arm to function inside the shoe, and a reciprocatory knife arranged to operate between said guide and said shear member, said guide being arranged to maintain said knife in shearing relation to said shear member and to sustain the severed material against the drag of the knife toward the interior of the shoe."
